United States Patent Office

Des. 230,081

Patented Jan. 22, 1974

230,081

PAPER TOWELING OR SIMILAR ARTICLE

Gordon D. Thomas, Neenah, Wis., assignor to Kimberly-Clark Corporation, Neenah, Wis.

Filed June 19, 1972, Ser. No. 263,866

Term of patent 14 years

Int. Cl. D5—06

U.S. Cl. D59—2 B

FIG. 1

FIG. 2

FIG. 1 is a plan view of a paper towel showing my own design; and

FIG. 2 is an enlarged fragmentary view thereof.

I claim:

The ornamental design for a paper toweling or similar article, as shown and described.
